UNITED STATES PATENT OFFICE.

LOUIS STEINBERGER, OF NEW YORK, N. Y.

BINDING-POST.

941,893.

Specification of Letters Patent. Patented Nov. 30, 1909.

Application filed April 2, 1909. Serial No. 407,893.

To all whom it may concern:

Be it known that I, Louis Steinberger, a citizen of the United States, and a resident of the city of New York, borough of Brooklyn, in the county of Kings and State of New York, have invented a new and Improved Binding-Post, of which the following is a full, clear, and exact description.

My invention relates to binding posts, my more particular purpose being to improve the clamping mechanism for holding wires, and also to provide for attaching quite a number of wires upon the same post.

My invention further relates to means for improving the facility and quickness with which a wire may be connected with or disconnected from a post without having to resort to the employment of any tools.

My invention further relates to means for improving the facility and quickness with which a wire may be connected or disconnected from a post without disturbing any of the remaining wires.

My invention further relates to mechanism for preventing loose parts associated with the post from becoming detached and thus getting lost.

My invention still further relates to the provision of a spring for exerting a yielding but firm pressure upon the wire or analogous member to be clamped.

More particularly stated, my invention comprehends a binding post having a central stem encircled by a spiral spring of metal, and adjacent to the ends of this spring clamping plates arranged in pairs, the plates of each pair being pressed together by the action of the spring and the outer edges of the clamping plates being slightly curved to facilitate the entrance of the wire therebetween.

My invention further comprehends certain details of construction for improving the general efficiency of the binding post and of various parts thereof.

Reference is to be had to the accompanying drawings forming a part of this specification, in which similar characters of reference indicate corresponding parts in all the figures.

Figure 1 is a perspective showing two of my improved binding posts mounted upon a terminal block and employed for the purpose of connecting together in various ways a considerable number of wires; Fig. 2 is a

substantially central vertical section through one of my improved binding posts showing the means for mounting the same upon a base, and further showing the various movable parts used for clamping the wires; Fig. 3 is a fragmentary view partly in elevation and partly in section, showing otherwise the same features as Fig. 2; Fig. 4 is a view partly in elevation and partly in section, showing the binding post as used for clamping only two large wires extending directly through the stem; Fig. 5 is a detail showing one way of mounting the stem upon a base, this view showing the stem before its top is spun outwardly as in Figs. 2, 3 and 4; Fig. 6 is a detail showing another way of mounting the stem in position upon a base, the stem in this instance not as yet being spun at its end; and Fig. 7 is a detail showing still another way of mounting the stem, which in this instance is double-ended and supported by a partition, the stem being as yet not spun.

A metallic sleeve 8 is threaded both internally and externally as indicated in Fig. 2, and is embedded flush with the top of a base 9 of insulating material. The external thread of this sleeve serves as a very effective anchorage, and also, in some instances, enables the sleeve to be removed, if desired, from the base. A stem 10 is provided at its upper end with a cavity 11 and is adapted to have its upper end spun, as indicated in Figs. 2, 3 and 4. In spinning the stem it acquires an annular bead 12 integral with it. The stem is provided with an annular flange 13 which gives it a good bearing upon the base 9. Bearing plates 14, 15, 16, 17, each of a general annular form, are slipped over the stem before the upper end of the latter is spun, and are retained permanently upon the stem, being unable to leave the same on account of the annular flange 13.

The stem 10 is provided at its bottom with a hole 18 the lower surface of which just grazes the upper edge of the flange 13. The stem is further provided with a hole 19 extending through its upper end at a point just below the annular bead 12. A spiral spring 20 encircles the middle portion of the stem and engages the plates 15, 16. The outer edge of each of these plates is cupped slightly toward the opposite plate, whereas the outer edges of the plates 14, 17 are

cupped slightly away from each other. The bearing plates 14, 15 thus have their outer edges turned away from each other, and this is also the case with the bearing plates 5 16, 17.

In order to secure a wire in the hole 18 the operator grasps the bearing plate 14 and raises it, thereby compressing the spring 20. The wire is next inserted through the hole 10 18 and the bearing plates released so that the pressure of the spring forces the bearing plate 14 directly downward upon the wire, pinning it against the upper surface 15 of the flange 13. Other wires 20^a, 21, 22, 23 may be connected with the binding post. In order to connect the wires 20^a, 21, they are simply forced in between the clamping plates 14, 15, as will be understood from Figs. 1, 2 and 3. Similarly the wires 22, 20 23 are clamped intermediate the clamping plates 16, 17. As indicated by Figs. 3 and 4, wires 24, 25 may also be connected, the wire 24 being inserted through the hole 18, and the wire 25 through the hole 19, in each 25 case the wire being held by pressure upon the adjacent clamping plate 14 or 17, as the case may be.

Integral with the stem 10 is a threaded portion 26 which screws into the sleeve 8, 30 as will be understood from Fig. 2, and is provided with a hole 27. The purpose of this hole can best be understood by reference to Fig. 5, which shows a slightly different form of base. In this instance the 35 stem is shown at 10^a and differs not at all from the stem 10 appearing in Figs. 2, 3 and 4, except in the fact that its upper end has not yet been spun. The lower end of the stem 10^a is provided with a threaded portion 26, or, in other words, is identical with the corresponding portion shown in Fig. 2 and has a hole 27 extending diametrically through it. The threaded portion 26 of the stem 10^a extends through a plate 28 of 40 45 trose. Engaging the lower end of the threaded portion 26 are revoluble nuts 29, 30 threaded internally and applied as indicated in Fig. 5. The hole 27 and the nut 30 may be employed for clamping an additional wire in position. For this purpose the wire is extended through the hole and the nut 30 is run down upon it.

In the construction shown in Fig. 6 the stem 31 is provided at its bottom with a 50 flange 32 and is mounted upon an anchorage 33 which is embedded in a base 34 of insulating material. The anchorage 33 is provided with a hole 35 extending through it and adapted to receive a smaller portion 60 of the insulating material. A vertically disposed partition 36 is sometimes used as indicated in Fig. 7. The stem 38 is provided with an elongated portion 39 having a flange 40 integral with it and revolvably en-

gaging this flange is a nut 41. The stem 65 38 is provided with a flange 42 integral with it.

In order to assemble the parts indicated in Fig. 7, the elongated portion 39 is extended through the partition 36 and the nut 70 41 is fitted upon the flange 40 and is tightened against the partition 36. This construction affords a double-ended binding post which, in other respects, is similar to those shown in the other figures. 75

I do not limit myself to the use of any particular metal or of any particular insulating material in the construction of the various parts of this binding post and parts associated with it. Neither do I limit myself to the exact form of binding post shown in the drawings. 80

Having thus described my invention, I claim as new and desire to secure by Letters Patent: 85

1. A binding post, comprising a stem, clamping plates encircling the same, means for preventing the easy removal of said clamping plates from said stem, and a spring for pressing said clamping plates apart in 90 the general direction of said stem.

2. A binding post, comprising a body portion provided with a flange, and further provided with a portion for connecting said body portion with a base, said stem being 95 further provided at its end opposite said flange with another flange, clamping plates disposed intermediate said flanges, and a spring member disposed intermediate said clamping plates. 100

3. A binding post, comprising a pair of movable clamping plates having their edges cupped in opposite directions to facilitate the entrance of a wire intermediate said clamping plates, and means for pressing one 105 of said clamping plates toward the other.

4. A binding post, comprising a pair of movable clamping plates, a stem threaded through said clamping plates, and a spring disposed intermediate said clamping plates 110 for forcing the same in opposite directions.

5. A binding post, comprising a stem provided with a flange, a movable clamping plate encircling said stem and disposed adjacent to said flange which forms a limiting 115 stop therefor, a second movable clamping plate, and means for forcing said second clamping plate toward said first-mentioned clamping plate by spring tension.

6. A binding post, comprising a body 120 member, a plurality of clamping plates of annular form arranged in pairs and encircling said body member, and a spring engaging two of said clamping plates and forcing the same in opposite directions. 125

7. A binding post, comprising a stem, and a pair of movable clamping plates mounted thereupon and adapted to receive a wire

therebetween, said clamping plates being cupped in opposite directions to facilitate the entrance of said wire to be clamped.

8. The combination of a stem, a pair of movable clamping plates mounted thereupon and adapted to secure a wire, another pair of movable clamping plates mounted upon said stem and adapted to secure another wire, and a spring disposed intermediate said pairs of clamping plates and compressing the same in opposite directions.

9. A binding post, comprising a stem provided with an annular flange spun outwardly therefrom and integral therewith, and clamping members slidably mounted upon said stem, one of said clamping members being movable relatively to another for the purpose of securing a wire therebetween.

10. A binding post, comprising a body member provided with a portion for securing it to a support, and further provided with flanges, clamping members connected to said body member and movable in opposite directions, and spring mechanism disposed between said clamping members for exerting pressure against them.

11. A binding post, comprising a body member provided with a portion for securing it to a support, and further provided with flanges, a pair of movable clamping members connected to said body member, and means for securing a conductor under spring tension between said pair of said clamping members.

12. A binding post, comprising a body member provided with a portion for securing it to a support, and further provided with a flange, a pair of movable clamping members, and a spring for forcing one of said clamping members toward another.

13. A binding post, comprising a body member provided with an integral portion for securing it to a support, and further provided with flanges, a plurality of clamping members, one being movable relatively to another and encircling said body member,

and means for securing a conductor under spring tension adjacent to each of said flanges.

14. In a device of the character described, the combination of a base of insulating material, a metallic member embedded in said base and having a portion extending therefrom, said metallic member being provided with flanges, clamping members mounted on said extending portion of said metallic member and movable relatively thereto, and a spring mechanism disposed intermediate said clamping members for exerting pressure upon said clamping members. 60

15. A binding post comprising a body member provided with flanges integral therewith, said body member being further provided with an integral portion for connecting it to a support, movable clamping members disposed intermediate said flanges, and a spring member disposed between two of said clamping members. 65

16. A binding post, comprising a stem provided with flanges, movable clamping plates mounted loosely upon said stem and disposed in pairs at the opposite ends of said stem, and a spring mechanism for pressing one of said clamping plates toward one of said flanges, and pressing another of said 75 clamping plates toward another of said flanges.

17. The combination of a stem provided with a flange, a pair of clamping plates movable relatively to said stem and to each other for the purpose of clasping a wire between said clamping plates, and a spring for forcing both of said clamping plates toward said flange. 80

In testimony whereof I have signed my name to this specification in the presence of two subscribing witnesses. 85
